United States Patent Office.

CYRUS LOMAX, OF PAOLI, INDIANA.

Letters Patent No. 91,756, dated June 22, 1869.

IMPROVED BOOT-CRIMP.

The Schedule referred to in these Letters Patent and making part of the same.

To all whom it may concern:

Be it known that I, CYRUS LOMAX, of Paoli, in the county of Orange, and State of Indiana, have invented certain new and useful Improvements in Crimping-Boards for Bootmaker; and I do hereby declare that the following is a full, clear, and exact description thereof, reference being had to the accompanying drawings, and to the letters of reference marked thereon, which form a part of this specification, and in which—

Figure 2 represents a longitudinal section of my crimping-device, and

Figure 1, a side elevation of the same.

Similar letters indicate like parts in all the figures.

My invention relates to improvements in the mode of crimping leather; and to this end,

It consists in the employment of a leather cap, provided with metal springs, and so constructed as to fit over the front edge of the crimping-board, in combination with such other devices as will be hereinafter set forth.

To enable others to make and use my invention, I will now describe its construction and operation.

In the accompanying drawings—

A represents an ordinary crimping-board, and

B, the cap, which consists of a piece of leather bent over and shaped like the front edge of the crimping-board.

a a is a rib, of iron, riveted to each side of the cap, near its lower edge.

b is a shoulder or recess, formed in the ribs a a near

the instep, the object of which will be hereinafter described.

C C C are steel springs, made and secured to the ribs a a, as seen in fig. 1, to hold the cap together in proper shape as the operation of crimping is performed.

The operation of my crimping-board is as follows:

The crimping-board A is placed, on its heel, on a stool of convenient height, and the leather to be crimped is laid across the edge of the said board. The cap B is then inserted over the leather, and pressed with the hand, sufficient to keep the leather in its place. Then by a pair of loose hooks, running up through the stool, immediately under the centre spring, which hook into the shoulder b, the cap is forced into the board A by the foot pressing against a strap attached to the hooks. By this arrangement leather can be crimped in one-third the time required in the ordinary way.

Having thus described my invention,

What I claim as new, and desire to secure by Letters Patent, is—

The cap, B, provided with ribs a a, in combination with the adjustable springs C C C, arranged to operate in connection with the crimping-board A, substantially in the manner and for the purpose set forth.

In testimony that I claim the foregoing as my own, I affix my signature in presence of two witnesses.

CYRUS LOMAX.
